UNITED STATES PATENT OFFICE.

EDWARD LAAS, OF ELGIN, AND HIRAM H. SPONENBURG, OF WADSWORTH, ILLINOIS.

RAILWAY-RAIL STAY.

SPECIFICATION forming part of Letters Patent No. 757,754, dated April 19, 1904.

Application filed December 18, 1903. Serial No. 185,340. (No model.)

To all whom it may concern:

Be it known that we, EDWARD LAAS, a resident of Elgin, in the county of Kane, and HIRAM H. SPONENBURG, a resident of Wadsworth, in the county of Lake, in the State of Illinois, citizens of the United States, have jointly invented new and useful Improvements in Railway-Rail Stays, of which the following, taken in connection with the accompanying drawings, is a full, clear, and exact description.

This invention relates to the class of rail-stays which are employed on railways and are secured to the rail and provided with abutments bearing on the sides of the cross-ties for the purpose of preventing the rail from creeping longitudinally.

The invention consists in a novel construction of the anticerping rail-stay which affords a more direct and positive hold on the rail and by the abutment of said stay against the side of the cross-tie assures prevention of longitudinal creeping of the rail.

In the accompanying drawings, Figure 1 is a side view of a railway-rail equipped with our improved anticerping stay. Fig. 2 is a transverse section of the same. Fig. 3 is a transverse section on the line X X in Fig. 2 viewed in the direction of the arrow. Fig. 4 is a top plan view of the anticerping rail-stay, and Fig. 5 is an isometric perspective view of a modification of the detail construction of one of the rail-gripping jaws of our invention.

Similar letters of reference indicate corresponding parts.

R represents one of the rails of a railway. A denotes one of the cross-ties which support said rail upon the road-bed. The arrow D indicates the direction in which the rail tends to creep. It is this creeping of the rail which is designed to be resisted by our improved rail-stay, which is constructed as follows: a and a' represent the rail-gripping jaws, which are disposed at opposite sides of the rail R and in position to abut against the side of the cross-tie A. These jaws are formed with horizontally-prolonged bottom bearings b, extending part way across the under side of the rail,

as shown in Fig. 2 of the drawings. The bearings b are out of contact with each other to allow the jaws to freely move into position to grip the base or flanges of the rail, which flanges serve as fulcrums for the jaws, which are guided rectilineally by the bearings b, 55 pressed onto the bottom of the rail. From the bottom of each of the bearings b projects a lug or perforated ear c to afford a hold for a suitable tie for drawing the jaws toward each other, so as to cause them to firmly and 60 securely grip the edges of the base of the rail. For this purpose we prefer to employ a bolt d, which passes through the perforated ears c c and is provided at one end with a head c', by which it engages one of the said ears, and 65 with a nut n, by which it bears on the other of said ears.

We do not limit ourselves specifically to the aforesaid means for tightening the bolt on the ears c c, inasmuch as said bolt may be provided with a nut on each end, or one of the said ears may be screw-threaded internally to serve the function of a nut, or in place of the nut n a key or wedge may be employed by providing the bolt with a slot or seat for the 75 reception of said key or wedge.

We preferably form the jaw a' slightly at an angle in relation to the jaw a, so that in applying said jaws in proper position for gripping the rail R the jaw a' will lie a short distance from the side of the cross-tie A, as illustrated in Fig. 4 of the drawings. The said arrangement of the jaws causes the jaw a' to be crowded toward a line parallel with the jaw a when subjected to severe strain in resisting the creeping of the rail. The said movement of the jaw a' causes the engaging portion thereof to obtain a firmer grip on the rail. One of the jaws, preferably the jaw a, which is provided with the longer bottom bearing b, is formed with a depending flange e, by which it abuts against the side of the tie, as more clearly shown in Fig. 1 of the drawings, which abutment is strengthened by a brace f, extending from the bottom of the 95 jaw to the flange or abutment e and formed integral therewith.

The detail construction of the jaw with its

bottom-bearing and lug or ear may be modified without depriving it of its essential features. One of such modifications is illustrated in Fig. 5 of the drawings, in which the tie-bolt-receiving lug or ear is of the form of channel l in the bottom bearing b adjacent to the gripping portion of the jaw α . The brace f in this case extends from the flange or abutment e to the under side of the channel l to reinforce the latter. We prefer, however to strengthen the jaws α α' by means of ribs r r , as shown in Fig. 1 and Fig. 4 of the drawings.

What we claim as our invention is—

- 15 1. A railway-rail stay consisting of two separate rail-gripping jaws fulcrumed on the rail-flanges and with horizontally-prolonged bottom bearings sustained out of contact with each other and abutting the side of the tie, lugs projecting from said bottom bearings, and a bolt engaging the lugs and provided with means for drawing the jaws into engagement with the rail as set forth.
- 20

2. A railway-rail stay consisting of separate laterally-movable rail-gripping jaws, each formed with a bottom portion bearing on the under side of the rail and with a depending lug, a bolt passing through the lugs and provided with a head on one end and with a nut on the opposite end, and an abutment depending from the bottom bearing of one of the jaws as set forth and shown.

3. A railway-rail stay consisting of separate laterally-movable rail-gripping jaws disposed at an angle in relation to each other and each formed with a bottom portion bearing on the under side of the rail and with a depending lug, a bolt engaging the lug and provided with means for drawing the jaws into engagement with the rail, and an abutment depending from one of said jaws as set forth.

EDWARD LAAS.

HIRAM H. SPONENBURG.

Disclaimer in Letters Patent No. 757,754.

DISCLAIMER.

757,754.—*Edward Laas, Elgin, and Hiram H. Sponenburg, Wadsworth, Ill. RAILWAY-RAIL STAY.* Patent dated April 19, 1904. Disclaimer filed November 9, 1908, by *Otto R. Barnett*, assignee.

Enters this disclaimer—

“To that part of the claim in said specification which is in the following words, to wit:

“1. A railway-rail stay consisting of two separate rail-gripping jaws fulcrumed on the rail-flanges and with horizontally-prolonged bottom bearings sustained out of contact with each other and abutting the side of the tie, lugs projecting from said bottom bearings, and a bolt engaging the lugs and provided with means for drawing the jaws into engagement with the rail as set forth.

“2. A railway-rail stay consisting of separate laterally-movable rail-gripping jaws, each formed with a bottom portion bearing on the under side of the rail and with a depending lug, a bolt passing through the lugs and provided with a head on one end and with a nut on the opposite end, and an abutment depending from the bottom bearing of one of the jaws as set forth and shown.” [Official Gazette, November 17, 1908.]

bottom-bearing and lug or ear may be modified without depriving it of its essential features. One of such modifications is illustrated in Fig. 5 of the drawings, in which the tie-bolt-receiving lug or ear is of the form of channel l in the bottom bearing b adjacent to the gripping portion of the jaw α . The brace f in this case extends from the flange or abutment e to the under side of the channel l to reinforce the latter. We prefer, however to strengthen the jaws α α' by means of ribs r r , as shown in Fig. 1 and Fig. 4 of the drawings.

What we claim as our invention is—

- 15 1. A railway-rail stay consisting of two separate rail-gripping jaws fulcrumed on the rail-flanges and with horizontally-prolonged bottom bearings sustained out of contact with each other and abutting the side of the tie, lugs projecting from said bottom bearings, and a bolt engaging the lugs and provided with means for drawing the jaws into engagement with the rail as set forth.
- 20

2. A railway-rail stay consisting of separate laterally-movable rail-gripping jaws, each formed with a bottom portion bearing on the under side of the rail and with a depending lug, a bolt passing through the lugs and provided with a head on one end and with a nut on the opposite end, and an abutment depending from the bottom bearing of one of the jaws as set forth and shown.

3. A railway-rail stay consisting of separate laterally-movable rail-gripping jaws disposed at an angle in relation to each other and each formed with a bottom portion bearing on the under side of the rail and with a depending lug, a bolt engaging the lug and provided with means for drawing the jaws into engagement with the rail, and an abutment depending from one of said jaws as set forth.
